UNITED STATES PATENT OFFICE

JOHN FRANCIS SHAW, OF LONDON, ENGLAND

ATTACHMENT FOR UMBRELLAS, WALKING STICKS, HANDLES OF TENNIS BATS, AND THE LIKE

Application filed November 20, 1925, Serial No. 70,336, and in Great Britain November 21, 1924.

This invention relates to improvements in attachments for umbrellas, walking sticks, handles of tennis bats and the like, such attachment being of the known kind comprising an arm or hook mounted on the stick, shaft or handle for facilitating the carrying of parcels or other objects and enabling the hand to be left free or unencumbered except for the stick. Such attachments have previously consisted of a single hook rigidly, removably or pivotally attached to the stick.

According to this invention, however, the attachment comprises a pair of hooks or arms, rigidly, removably or pivotally mounted on or in the stick or the like near that part of the handle usually gripped by the hand, one arm projecting, or being capable of projecting, upwards from one side of the stick being adapted to serve for the suspension of a parcel of other object while the other arm, projecting, or being capable of projecting downwards from the other side of the stick, serves for the suspension of the stick, umbrella or the like from a hook or rack on the wall or other object or from a pocket or other part of a person's dress. If the hooks are fixed, they may either be fixed on or in the stick or they may be clamped or clipped to the stick. Or, on the other hand, the hooks, which are conveniently made integral, may be pivoted in a slot in the stick or the hooks with their pivot are mounted in a casing which is inserted and fixed in the slot, or the pivots may be outside of the stick.

And in order that the invention may be readily carried into effect, reference will be made to the accompanying drawings, in which:—

Figure 1 is a view in which the hooks are mounted in a casing.

Figure 2 is a side elevation of the casing.

Figure 3 is an end elevation thereof.

Figure 4 is a developed plan view of the mount of a modification.

Figure 5 is an elevation of the apparatus applied to a stick on the left hand side thereof.

Figure 6 is a similar view on the right hand side thereof.

Figure 7 is a plan view, and

Figure 8 is a vertical section of another modification combined with a device for holding together the tips of the ribs of an umbrella.

In carrying the invention into effect as shown in Figs. 1, 2 and 3, the stick *a* is provided with hooks *b*⁵ and *c*⁵ which are pivotally mounted at *o*² in a casing *r* comprising two long sides united at the top and bottom by narrow strips *r'* *r*² and adapted to fit in a slot in the stick and this casing is conveniently furnished with a spring *s* riveted at one end to or integral with the casing. This spring, co-acting with suitably formed surfaces *v* *v'* angular to each other on the central part or boss of the double hook holds them either in the closed or the extended position. The hook may also be provided with a projection or knob *t* which on being pressed downwards with the finger or thumb, causes the hooks to project beyond the stick for use in the dotted position and on pressing the said knob upwards, the hooks are caused to return and enter the casing so that their outer sides are flush with the exterior of the stick.

As shown in Figures 4 to 7 inclusive, the band *d*⁷ of spring steel or other suitable elastic metal is furnished with two pairs of perforated lugs *f*² and *f*³ in which are mounted the hooks marked *b*⁷ and *c*⁷. The band is narrow at one end and furnished with a small projection or hook *g*⁷ which is adapted to engage in any one of the slots *w*. The band *d*⁷ is, moreover, provided with two tongues *x* which are bent outwards slightly to form springs. The hooks *b*⁷ and *c*⁷ are furthermore flattened at *y* near the ends of their shanks and these flattened portions *y* are adapted to engage with the spring tongues *x* when the hooks *b*⁷ and *c*⁷ are mounted in the perforated lugs *f*² and *f*³ respectively. The hooks proper are bent so as to lie as close as possible to the stick *a* when in their folded positions. Owing to the flat shape of the shanks of the hooks and the elasticity of the tongues *x*, the hooks are adapted to be forcibly held in their extended positions when the flats *y* engage the spring tongues and also in the folded condition because the edge of the flat in each case has moved past

the dead centre and is pressed by the said tongue.

The construction shown in Figure 8 is very similar except that the band d^8 is endless being a ring, slideable on a sleeve z , provided with a bead or flange at each end to prevent the band from coming off. The sleeve z is secured to the stick by a pin passing through a hole z' . The band or ring d^8 is furnished 16 at the bottom with a skirt-like extension d^9 to receive the ends of the umbrella ribs a^8 and perforated to receive the hooks which are otherwise fashioned and mounted as described with reference to Figures 4 to 7. As 15 in that case also there are two spring tongues x x' adapted to engage the flattened shanks y of the hooks b^7 and c^7 .

I claim:

1. An attachment for an umbrella stick 20 comprising, in combination, a sleeve for encircling the stick, a ring slideable on the said sleeve, a skirt-like extension on said ring adapted to engage the tips of the umbrella ribs, means for preventing the ring from being 25 coming detached from the sleeve, a hook pivotally mounted on the ring so as to project above the sleeve and adapted to engage an object to support the umbrella, a hook, pivotally mounted on the ring so as to project below the latter and adapted to support an 30 object hung thereon, and elastic means for holding the hooks in the extended and folded conditions, respectively.

2. An attachment for an umbrella stick 35 comprising in combination, a sleeve for encircling the stick, a flange at each end of the said sleeve, a ring slideable on the said sleeve, a flange at the top of the said ring and provided with two perforations opposite to each other, two spring-tongues, and a skirt-like extension at the bottom of said ring adapted to engage the tips of the umbrella ribs and provided with two perforations opposite to each other, a hook with a flattened shank, pivotally 40 mounted on the perforations on one side of said ring so as to project above the latter and adapted to support the stick, a hook with a flattened shank pivotally mounted in said perforations at the other side of the said ring 45 so as to project below the latter and adapted to support an object hung thereon, the flattened portions of the shanks of the hooks being adapted to be engaged by the said spring tongues.

3. An attachment for a stick, comprising in combination, a band for encircling the stick, projecting arms pivotally mounted independently of each other on opposite sides of the said band, one of the said arms adapted to 50 rest in the closed condition close to the stick and parallel therewith and to be moved outwardly into such a position as to enable it to engage an object to support the stick, the other arm similarly adapted to rest in the 55 closed condition, close to the stick and adapt-

ed in the extended condition to support an object thereon, and means for limiting the outward movement of the said arms.

4. An attachment for a stick comprising a support, means to hold the latter on the stick, 70 said support carrying an upwardly and a downwardly directed hook movable into engagement with said stick, said support including means for holding both hooks in extended or non-extended position.

5. An attachment for a stick, comprising a sleeve, means to hold the latter on the stick, 75 said sleeve carrying an upwardly and a downwardly directed hook movable into engagement with the stick, said sleeve including 80 means for holding both hooks in extended or non-extended position.

JOHN FRANCIS SHAW.
